No Drawing. 6 Pages Specification

A process of treating industrial waste water containing a dispersed elastomer such as neoprene in a concentration of 0.2 to 10.0 weight percent by (a) adding a coagulating agent such as calcium hydroxide or aluminum sulfate, (b) adding fly ash, preferably simultaneously, in the amount of at least one part fly ash to one part of elastomer and (c) agitating the mixture to form a water slurry of non-sticky coagulum. The fly ash renders the coagulum non-sticky allowing the slurry to be pumped and piped for further treatment without processing delays such as blockages and pump stops.
